UNITED STATES PATENT OFFICE.

FRANK HEAZLE, OF BREWER, MAINE.

DESIGN FOR A RUBBER PIN-PLATE FOR METALLIC HAIR-BRUSHES.

SPECIFICATION forming part of Design No. 17,372, dated June 7, 1887.

Application filed April 9, 1887. Serial No. 234,310. Term of patent 7 years.

To all whom it may concern:

Be it known that I, FRANK HEAZLE, a citizen of the United States, residing at Brewer, in the county of Penobscot and State of Maine, have invented a certain new and useful Design for Rubber Pin-Plates for Metallic Hair-Brushes; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention and is a front view. Fig. 2 is a section taken where the broken line $x x$ is marked on Fig. 1.

This design has relation to rubber pin-plates for metallic hair-brushes; and it consists in the novel form and configuration of the oblong

plate surrounded by the double bead, as hereinafter shown and described.

The plate indicated at A is of oblong shape and is formed with a marginal rim or heading, B, grooved or channeled parallel to the edge of the plate, as shown at C. This configuration gives the plate a finished appearance.

What I claim, and desire to secure by Letters Patent, is--

The design for a rubber pin-plate for metallic hair-brushes herein shown and described, consisting of the oblong plate A, surrounded by the double bead B, substantially as set forth.

In testimony whereof I affix my signature in presence of two witnesses.

FRANK HEAZLE.
